UNITED STATES PATENT OFFICE.

SVEN ROLFSON-SCHMIDT, OF HUNTINGTON, NEW YORK.

DOOR-SPRING.

1,084,111.

Specification of Letters Patent. Patented Jan. 13, 1914.

Application filed May 23, 1913. Serial No. 769,463.

To all whom it may concern:

Be it known that I, SVEN ROLFSON-SCHMIDT, a citizen of the United States, residing at Huntington, in the county of Suffolk and State of New York, have invented new and useful Improvements in Door-Springs, of which the following is a specification.

This invention relates to door springs; 10 and it has for its primary object the provision of a device of this character which can be readily applied to an ordinary hinge and which will include buffers which are adapted to engage against surfaces of the 15 door and door casing in such manner as will prevent undue marring of the surfaces of these parts while the hinge is in use.

With these and other objects in view, the 20 invention consists of certain novel features of construction, combination and arrangement of parts, as will be hereinafter described and claimed.

In the accompanying drawings:—Figure 1 is a front view of the spring, showing the 25 application thereof to the hinge of a swinging door; Fig. 2 is a perspective view of the spring removed from the hinge.

The spring comprises identical sections A and B each constructed of a single length 30 of wire bent in its main length into a coil 1 having many convolutions preferably of an internal diameter so as to accommodate therein the knob end 2 on the pintle or other desired portion of the hinge 3. From 35 the coil 1 each section is provided with a horizontal arm 4 having its free end formed with an eye 5 in which is fitted a stem 6 of a buffer disk 7, the latter being constructed of rubber, felt or an equivalent elastic material. The opposite terminal or arm 8 of 40 the coil 1 extends in an opposite direction from the arm or terminal 4 and as illustrated it is provided with a vertical branch 9 having a vertical eye 10 in which is secured 45 the stem 11 of a buffer disk 12, the latter being identical with the previously described disk 7 of the arm or terminal 4. The extremity of the branch 9 is provided with a horizontal guide eye 13 which slidably receives 50 the branch 9 of the other section of the spring, as clearly shown in Fig. 1.

Adjacent ends of the branches 9 of the companion sections A and B are embraced by a coiled spring 14 whose ends are confined 55 against the guide eyes 13 of said

branches 9 whereby the coils 1 of said sections A and B are operatively held aligned with one another and properly associated with the knobs 2 of the hinge B. This construction is also such that the two sections 60 A and B may be distended relatively so that they may be readily made to accommodate themselves to hinges of varying lengths.

Under the action of the coils 1 and the fact that the sections A and B are connected with each other, as specified, the buffer disks 12 of the arms or terminals 8 will tend to move in the direction of the buffers 7 of the arms or terminals 4, and, as a consequence, the buffers 12 will be effectually 70 confined against adjacent surfaces of the door casing C, while the buffers 7 will be held in similar contact with adjacent surfaces of the swinging door D, as shown in Fig. 1. In this manner pressure of the 75 branches 4 and 8 of the spring will operate to immediately return the door to a closed position after the same is opened.

Through the fact that the sections A and B are slidably and yieldingly connected together they will be accurately held in position relatively of the hinge without the provision of permanent fastening devices, while changing the construction of the hinge to accommodate the spring will be obviated. 85 When the convolutions of the coils 1 are brought under tension during the operation of moving the door D to opened or closed positions the arms 4 and 8 respectively will be free for slight horizontal movements 90 over the adjacent surfaces of the casing C and door D, carrying the buffers 7 and 12 respectively therewith and causing the same to engage yieldingly against said casing C and door D so as to prevent the same from 95 being scratched or otherwise marred.

From the foregoing description, taken in connection with the accompanying drawings, the construction and operation of the invention will be readily understood without requiring a more extended explanation. 100

Various changes in the form, proportion and the minor details of construction may be resorted to without departing from the principle or sacrificing any of the advantages of this invention as claimed. 105

Having thus described my invention, what I claim is:—

A spring for hinges comprising relatively 110 adjustable identical sections, each having a

pair of oppositely extending arms and an intermediate pintle receiving coil, means for normally moving the sections toward each other to confine the coils against the pintle, 5 the journals of the arms being respectively engaged against the door and door casing and confined thereagainst under the action of the coils, and buffers bearing against the

door and door casing successively and secured to the terminals of said arms. 10

In testimony whereof I affix my signature in presence of two witnesses.

SVEN ROLFSON-SCHMIDT.
